TISSUE DISPENSER

Louis D. Perret III, Box 417,
St. Charles Parish, La. 70047

Filed July 25, 1972, Ser. No. 274,862

Term of patent 14 years

Int. Cl. D6—06

U.S. Cl. D6—96

FIG. 2.

FIG. 1.

FIG. 3.

FIG. 4.

FIG. 1 is a perspective view taken from the front, side and top of a tissue dispenser showing my new design;

FIG. 2 is a top plan view thereof, the bottom being plain, except for a conventional dispensing slot, and unornamented;

FIG. 3 is a front elevational view thereof; and

FIG. 4 is an elevational view taken from the side shown in FIG. 1, the opposite side being a mirror image of the side shown.

I claim:

The ornamental design for a tissue dispenser, as shown and described.
